UNITED STATES PATENT OFFICE

91,915

DESIGN FOR A FLOODLIGHT

Jacob H. Wise, Chicago, Ill.

Application September 20, 1933, Serial No. 49,299

Term of patent 14 years

To all whom it may concern:

Be it known that I, JACOB H. WISE, a citizen of the United States, residing at Chicago, in the county of Cook and State of Illinois, have invented a new, original, and ornamental Design for a Flood Light, of which the following is a specification, reference being had to the accompanying drawing, in which—

I claim:—

The ornamental design for a flood light, as shown.

In testimony of which I affix my signature.

JACOB H. WISE.
